UNITED STATES PATENT OFFICE.

BUNNOSUKE OMOTO, OF GRANGER, WYOMING.

BIT.

Specification of Letters Patent. Patented June 20, 1916.

1,188,309.

Application filed February 9, 1916. Serial No. 77,201.

To all whom it may concern:

Be it known that I, BUNNOSUKE OMOTO, a citizen of the United States, residing at Granger, in the county of Sweetwater and 5 State of Wyoming, have invented new and useful Improvements in Bits, of which the following is a specification.

This invention relates to a bit which may be used to restrain an unruly horse.

10 The primary object of this invention is to provide a bit of the class described which is provided with a removable curb member so arranged that a pull upon the rein or bridle connected with the bit will cause the 15 curb member to press against the underside of the under jaw of the animal.

Another object of the invention is to provide the bit with arms for supporting the curb member which have openings arranged 20 in their free ends to permit the removal or the insertion of the curb member as the occasion requires so that the bit may be used with or without the curb member, as desired.

25 A still further object of the invention is to provide the arms upon the side bars of the bit with rectangular shaped openings, so that when the curb member has its reduced extension disposed in the said openings the 30 curb member will be prevented from turning when in contact with the lower jaw of the animal in whose mouth the bit is positioned, one of said arms having a finger providing a passage for the reduced end of the curb 35 member which is to be positioned in the opening in said arm.

A still further object of the invention is to provide a bit of this character having a curb member which is positioned exteriorly of the horse's mouth and normally 40 is out of contact with the underside of the lower jaw of the animal so that the animal is not annoyed by the curb member attached to the bit.

45 With these and other objects in view the invention resides in the novel combination and arrangement of parts which will be hereinafter described and particularly pointed out in the claims.

50 The preferred embodiment of the invention has been illustrated in the accompanying drawing, although no restriction is necessarily made to the precise details of construction therein shown, as changes, alterations and modifications within the scope of

the claims may be resorted to when so desired.

In the drawing: Figure 1 is a side elevation of a bit constructed in accordance with the invention and showing the same applied to the mouth of a horse, Fig. 2 is a perspective view of the bit removed from the mouth of the animal, Fig. 3 is a perspective view of the curb member detached from the bit.

65 Like characters of reference denote corresponding parts throughout the several views in the drawing.

Referring now to the drawing in detail the numeral 1 designates the mouth piece 70 of the bit which, has arranged at opposite ends thereof and extending above and below said mouth piece the usual side bars 2 the upper ends of which are provided with eyes 3 for receiving straps of the head stall 75 by means of which the bit is retained in the mouth of the animal while the lower ends of the side bars 2 are provided with the usual ring 4 to which the rein or bridle may 80 be connected in the usual manner.

Extending rearwardly from the side bars 2 between the mouth piece 1 and the rings 4 are spaced parallel curb members supporting arms 5 each of which is provided near 85 its free end with a rectangular shaped opening 6. One of the arms 5 gradually decreases in thickness toward the opening 6 therein and is provided at one end with a finger 7 having a portion thereof bent to overlie in spaced relation the opening 6 in 90 said arm and a portion of the arm adjacent said opening to provide an entrance to the opening indicated by the numeral 8. A cross bar 9 is provided and has its opposite ends reduced to provide laterally extending tenons 10, said tenons being rectangular in shape in cross section and adapted to be positioned within the openings 6 in the arms 5. A curved arm 11 is formed 95 integral with the cross bar 9 between its ends and is provided upon its outer or free end with an enlargement 12.

100 It will of course be understood that when it is desired to use the bit without the curb member the bit is positioned and retained in the animal's mouth in the usual manner and that the arms 5 in no way interfere with the movement of the head of the animal.

105 When the bit is applied to an unruly animal and it is desired to apply the curb mem- 110

ber to the bit the same can be done by placing one of the tenons on the cross bar 9 in the opening 6 in one of the arms 5. The other tenon upon the cross bar 9 is now positioned within the entrance passage 8 to the opening 6 in the other arm 5 and with the cross bar 9 in this position the remaining tenon can be passed into the remaining opening 6 in the bar 5 which gradually decreases in thickness toward the opening 6.

From the above statement it will be seen that the curb member can be applied to the bit without the hands of the rider of the horse being placed in such position as to enable the animal to bite and thus when the curb member has been applied to the bit the lower portion of the under jaw of the animal bearing upon the enlargement 12 will prevent casual displacement of the bar 6 from the slot 8 in the arm 5.

When the curb member is in place and a pull is exerted upon the rein or bridle connected with the rings 4 the curb member will be moved to such position as will cause the enlargement 12 on the end of the arm 11 to exert sufficient pressure upon the underside of the lower jaw of the animal to render the most unruly animal manageable.

From the foregoing statements taken in connection with the accompanying drawing

it is at once apparent that a bit has been provided which is simple in construction, inexpensive of manufacture and highly efficient in use.

Having thus described the invention, what is claimed as new, is:

1. A bit having arms inclining rearwardly from the side bars below the mouth piece, and a bar removably mounted in the end of said arms and provided with an extension between its ends.

2. A bit having downwardly inclining arms upon the side bars below the mouth piece, each having an opening in one end, a cross bar provided with reduced portions for disposition within said openings, and an arm formed integral with said bar between its ends and provided upon its free end with an enlarged portion.

3. A bit having a cross bar provided with reduced extensions at opposite ends rectangular in shape in cross section, a curved arm formed integral with said bar between said extensions, arms upon the side bars of the bit provided with openings for receiving said extensions, and a finger upon one of said bars overlying a portion of said arms to provide a passageway into said opening.

In testimony whereof I affix my signature.

BUNNOSUKE OMOTO.
